UNITED STATES PATENT OFFICE.

ALEXANDER ZDANCEWICZ, OF LANSFORD, PENNSYLVANIA.

CARPET-CLEANER.

1,300,323.

Specification of Letters Patent. Patented Apr. 15, 1919.

Application filed June 8, 1918. Serial No. 238,840.

To all whom it may concern:

Be it known that I, ALEXANDER ZDANCEWICZ, a citizen of the United States, residing at Lansford, county of Carbon, and State of Pennsylvania, have invented certain new and useful Improvements in Carpet-Cleaners, of which the following is a specification.

This invention relates to improvements in

carpet sweepers, and has as its special object the provision of a manually operated apparatus by means of which a carpet, rug or floor may be thoroughly swept and the sweepings delivered to a container combined with the apparatus.

A further object is to provide means whereby an adjustable contact of the brushes with the floor is obtained.

These and other like objects are attained by the novel construction and combination of parts hereinafter described and shown in the accompanying drawings, forming a material part of this disclosure, and in which:

25 Figure 1 is a side elevational view showing a carpet sweeper made in accordance with the invention.

Fig. 2 is a horizontal sectional view taken on line 2—2 of Fig. 1.

30 Fig. 3 is a vertical sectional view taken on line 3—3 of Fig. 2.

Fig. 4 is a fragmentary horizontal sectional view taken on line 4—4 of Fig. 3, and

35 Fig. 5 is an enlarged fragmentary sectional view, showing the means by which adjustment of the brushes can be obtained.

The apparatus is comprised of a metallic casing having side walls 10 and 11 with 40 which is formed a cover 12, curved downwardly at the front 14, and bent downward at the back forming an angular element 15, terminating in an inturned plate portion 16, as can best be seen in Fig. 3.

45 Engaged with the element 15 is a hub-like projection 18 to which is attached an operating handle 19, extending angularly rearward and upward so as to be conveniently manipulated.

50 Journalized transversely in the side walls 10 and 11, is a front shaft 20, having secured upon it a cylindrical brush 22, another shaft 23 passing through the side walls at the rear has secured upon it a smaller cylindrical brush 24. Mounted upon the end of the shaft 20, extending through the side

wall 11, is a spur gear 26 meshing with an intermediate gear 27, journaled upon a stud 28 firmly set in the side wall 10, the teeth of the intermediate gear being meshed with the 60 teeth of the pinion 29, fixed upon the end of the shaft 23 extending through the wall 10, thus causing both of the revolving brushes 22 and 24 to rotate in the same direction as the apparatus is pushed forward over any 65 relatively level surface.

Secured to the inner side of the plate 16 is a bar 30 and a pair of substantially triangular plates 32 are affixed upon the rear casting wall 16, joined at the top by a transverse 70 plate 33, and having an angular plate 34, extending in at the bottom, forming a curved plate 35, extending toward the front of the apparatus, closely adjacent to the periphery of the brush 24. Connected to these rear plates 32 is a sack 38 comprised of flexible material and extending to the rear of the apparatus, being partially supported by a wire link connection 39 engaged with the hook 40 set in the handle element 19. 80

Formed with the front element 14 upon each side thereof are enlargements 42 containing curved cylindrical openings 43, and having extensions 44 upon their inner sides, as can best be seen in Fig. 5. 85

Suited to be slidably received within the openings 43 are rods engaged with a roller 46 which extends transversely across the extreme front end of the apparatus and which is capable of bearing a portion of the weight 90 so as to relieve the operator of the same.

As the brushes become worn, or if it is desired to have them come into closer contact with the surface, the rods 45 may be pressed upwardly into the opening 43, and, 95 due to their frictional engagement in the opening 43, are capable of maintaining themselves in position, limit pins 47 being set in the inner sides of the rods adapted to be operated within the slot 48, formed in 100 the extension 44.

In operation, the apparatus is moved over the surface of the carpet, causing the brushes to rotate, carrying the dust and accumulations rearward and forcing the same over 105 the curved plate 35, into the sack 38, which is engaged with the extension 32 in such manner as to be readily removed therefrom, and as before noted, when the brushes have become worn or for other reasons it is desired to maintain a more effective pressure upon the surface of the carpet, the rods 45

are pressed upwardly into the openings 43 thereby lowering the entire apparatus.

Having thus described my invention what I claim as new and desire to secure by Letters Patent, is:

In a carpet sweeper of the character described, having a curved front edge, enlargements to both sides of said front edge containing curved cylindrical openings or channels, slotted extensions at the lower ends of

said enlargements, rods frictionally engaging the inner walls of said channels, a roller at the lower end of said rods, and limit pins set in the inner sides of said rods adapted to be operated within the slot of said extensions, substantially as described, and for the purpose set forth.

In testimony whereof I have affixed my signature.

ALEXANDER ZDANCEWICZ.
